UNITED STATES PATENT OFFICE.

AUGUST W. HERR, OF CHICAGO, ILLINOIS.

VAULT COVER AND VENTILATOR.

SPECIFICATION forming part of Letters Patent No. 284,203, dated September 4, 1883.

Application filed January 8, 1883. (No model.)

To all whom it may concern:

Be it known that I, AUGUST W. HERR, a citizen of the United States of America, residing at Chicago, in the county of Cook and State 5 of Illinois, have invented a new and useful Improvement in Vault-Covers and Ventilators, of which the following is a specification, viz:

This invention relates to improvements in 10 ventilating-registers, vault-covers, and similar articles; and it consists in certain novel details of construction, which will be hereinafter more fully described, and pointed out in the claims.

15 In order to enable others skilled in the art to which my invention appertains to make and use the same, I will now proceed to describe its construction and operation, referring to the accompanying drawings, in which—

20 Figure 1 is a plan view of my device; Fig. 2, a side view of the same; Fig. 3, a view of one of the hinged sections, and Fig. 4 a sectional view, somewhat enlarged, of one-half of my cover or frame and one of its hinged 25 sections.

A represents a cast frame, of circular, rectangular, or any desired form, provided with a central cross or division bar, A', and having its inner under edges rabbeted out for the reception of two or more doors or sections, B, which are secured to the central division-bar, A', by strap-hinges *a a*, as shown. These sections are arranged to be opened and closed and held in any position by means of any desired devices—as, for instance, the use of spring-knobs or rods adapted to be grasped by the hand.

The upper side of the frame A is formed or provided with gratings C, slightly raised above 40 the frame, as shown, which effectually protect the hinged sections from injury.

The hinged doors or sections B B are each a skeleton frame, having their inner and lower edges or corners rabbeted out, as shown in 45 Fig. 4, and a plate of glass inserted, which rests upon lugs *b b*, cast upon one side of the

section and upon plugs or pins *b' b'*, which are driven through holes in the opposite side.

It will be readily understood that when this device is used to cover coal-holes and similar places in a sidewalk, light is given to the vault by the glass panels, and either one or both of the hinged sections may be opened for ventilation without danger to passers-by, as the grating C is not disturbed. The grating 55 may be made removable for stowing away coal, &c., and the sections closing against rubber packing *c* in the rabbets of the frame A prevents any water from reaching the interior of the vault, and any snow or rain accumulating 60 upon the glass beneath the grating passes off through small openings *c'* in the raised frame of said grating.

When used as a ventilator or register in the interior of houses, the glass panels admit of a 65 view of the ventilating-shaft or the room below without disturbing the frame, and whenever found desirable one of the hinged sections B may be dropped to admit more heat or moist air to pass into the room. 70

Having thus fully described my invention, what I claim as new, and desire to secure by Letters Patent, is—

1. In a ventilating vault-cover, the combination of the frame A, hinged sections B B, and removable grating C, substantially as described. 75

2. A vault-cover or ventilator-frame consisting of the frame A, having cross-bar A', raised grating C, provided with drain-openings *c'*, one or more hinged sections, B, having glass panels supported by lugs *b b* and pins *b' b'*, closing against a rubber packing, *c*, all constructed and arranged to operate substantially as and for the purpose set forth. 85

In testimony whereof I affix my signature in presence of two witnesses.

AUGUST W. HERR.
